(57) **CLAIM**

The ornamental design for a console for a purge cassette of a catheter pump, as shown and described.

DESCRIPTION

1. Console for a purge cassette of a catheter pump

1.1 : Front perspective

1.2 : Back perspective

1.3 : Front

1.4 : Back

1.5 : Left

1.6 : Right

1.7 : Top

1.8 : Bottom

Figure 1.1 shows a front perspective view of the console for a purge cassette of a catheter pump; figure 1.2 shows a back perspective view of the console for a purge cassette of a catheter pump; figure 1.3 shows a front view of the console for a purge cassette of a catheter pump; figure 1.4 shows a back view of the console for a purge cassette of a catheter pump; figure 1.5 shows a left view of the console for a purge cassette of a catheter pump; figure 1.6 shows a right view of the console for a purge cassette of a catheter pump; figure 1.7 shows a top view of the console for a purge cassette of a catheter pump; figure 1.8 shows a bottom view of the console for a purge cassette of a catheter pump.

The broken lines in the figures showing of a console for a purge cassette of a catheter pump are for the purpose of illustrating portions of the article and form no part of the claim.

1 Claim, 8 Drawing Sheets
